UNITED STATES PATENT OFFICE.

THOMAS J. BURGESS, OF PETERSBURG, VIRGINIA.

DENTAL BITE APPARATUS.

Application filed December 9, 1926. Serial No. 153,546.

This invention is related to dental apparatus and particularly to those devices for guiding the lower jaws of patients while dentists are engaged in taking impressions of the 5 patients' teeth in preparation for the construction of dental work as, for example, plates.

In order to properly construct formations for artificial teeth, it is necessary for the 10 dentist to know the exact shape of the jaw and teeth within the mouth. It has been found that in taking impressions of the teeth and jaw with the wax or compound used for the purpose, that the patient has a tendency 15 to throw the lower jaw outwardly to an extended and unnatural position. The result is that an impression in the wax or compound is obtained which is not only unnatural but is misleading to the dentist and 20 sometimes result in the construction of artificial teeth structures which are inaccurate. To avoid this, trial plates are sometimes made.

Attempts to provide means for guiding the 25 lower jaw have been made, but those apparatuses for this purpose, with which I am familiar, have no means for positively and accurately guiding the lower jaw to the proper position while at the same time permitting a ready release of the lower jaw 30 when the bite, to produce the impression in the wax or compound, has been completed.

The primary object of this invention is the provision of an improved apparatus for 35 guiding to a proper position the lower jaw of a dental patient having an impression of the teeth taken, thus insuring an impression with the teeth in normal registration.

Another object of this invention is the provision of such an apparatus which will have 40 a chin-holding member which is positively limited in its action relative to the head of the patient.

A further object of this invention is the 45 provision of such an apparatus having a chin-holding member which when in place will draw the chin to its natural position when the jaws of the patient are being closed, but will release the jaw as soon as the latter 50 begins to open.

Another and further object of this invention is the provision of such an apparatus which not only produces a bite in the wax which is so accurate that the preparation of

trial plates is unnecessary but which will 55 have no parts to be sterilized after use.

Other and further objects of the invention will be apparent to those skilled in the art, from a reading of the complete specification.

Referring to the accompanying drawing 60 wherein I have illustrated one embodiment of my invention,

Fig. 1 is a side view of the apparatus in place on the head of a patient.

Fig. 2 is a front elevation of the apparatus 65 by itself.

Fig. 3 is a top plan view of the apparatus.

Like reference characters refer to the same or similar parts throughout the several views of the drawing.

The main supporting device of my invention includes a portion for contacting at the rear of the patient's head and a portion for contacting at the top of the patient's head. In the embodiment shown in the accompanying drawings, I provide a back board 10 and a top board 11 hinged together at 12. The hinge is so related to the boards 10 and 11, that they may close together but may not open farther than the angled position shown 70 in Fig. 1. It will be understood that the purpose of the hinge is to compactly fold the parts 10 and 11 together.

The back board 10 is preferably, though not necessarily, of a shape conforming to the 75 outline of the head of a patient as shown in Fig. 2. This back board 10 is shown as of sufficient length to engage not only the back of the head but also the back of the shoulders as well. The top board 11 contacts with the 80 top of the head as shown in Fig. 2 and is preferably inclined downwardly as illustrated to gain a firm grip upon the head. The back and top boards may be of wood, metal or any other suitable material.

Secured to the rear of the back board 10 is a swivel plate 13 in which is swiveled a screw 14 which is provided with a wing 15 for turning the screw. On the screw 14 is located an adjustment nut 16 which carries 100 an elongated bearing 17. Within the bearing 17 is a shaft 18 which is freely movable in its bearing 17 both axially and rotatively. At the outer portion of each end of the shaft 18 is pivoted two side members 19 of the 105 retractor. These side members 19 are attached at their other ends to the ends of the chin-engaging member 20 of the retractor.

The side members 19 of the retractor are constructed of metal or wood or any other suitable material. The chin-engaging member 20 is made of some suitable soft flexible material as cotton or leather, the upper and lower edges being preferably bound with a cord to form a bead at the edge. This causes a pocket to be formed for the point of the chin, the beads being above and below to assist 5 the chin-engaging member to stay in place.

10 The side members 19 are provided with a series of openings to receive the shaft 18 in any one of a plurality of adjustments. These holes are close enough together to provide, 15 with the co-operation of the adjustment of the screw 14, a means for adjusting in any position of the retractor necessary for the proportions of the head of the particular patient, the impression of whose mouth is being taken.

20 In using my invention, the top and back boards 10 and 11 are put in place, the screw 14 is turned so as to drive the nut 16 inwardly toward the back board 10. One side member 19 is put in place on the shaft 18. The chin-engaging member 20 is brought around and one of the openings of the other side member made to register with the shaft 18. While this putting the parts in position 25 is taking place and subsequently during the adjustment, the jaws should be held closed with the condyles of the inferior maxillary firmly in the glenoid fossæ. While in this position, the screw 14 by its wing 15 is turned 30 until the chin-engaging member 20 of the retractor is so snug against the chin that no forward movement of the jaw may take place. The patient is now ready to receive the wax for the impression.

35 40 The parts are preferably so arranged that the plane passing through the axis of the shaft 18 and the point of contact between the flexible chin-engaging member 20 and the chin, will be below the condyles of the inferior maxillary or if not below, then not higher than the same. It is obvious that as 45 the jaw closes, with the retractor adjusted as above described, the jaws will be brought back to their normal and proper closed position.

50 After the adjustment, the wax is placed in the mouth with the retractor in place. The patient now closes his jaws which are not affected by the presence of the wax since the 55 retractor causes the proper registry of the teeth or gums.

50 With my invention, it is clear that not only will a proper bite be obtained, but there will be no parts which require sterilization. This accuracy which I have found to be incident to the use of my invention makes the preparation of trial plates unnecessary and this saves time for both operator and patient.

65 A very particular feature of my invention when constructed as described, is that the

jaw when open is freely movable yet always is caused to close to the proper position.

While I have described and shown in detail an embodiment of my invention, I desire to have it understood that I do not limit myself to the exact showing and that modifications and changes may be made without departing from the spirit of my invention and within the scope of the appended claims.

Having described my invention, what I claim is:

1. A dental bite apparatus comprising a stiff support having a portion in position to engage the rear of the patient's head, another portion in position to engage the back of the shoulders and another portion in position to positively engage the top of the head of the patient, and a jaw retractor pivoted to the support and at a point to the rear of that occupied by the condyles of the inferior maxillary of the patient.

2. A dental bite apparatus comprising a stiff support having a portion in position to engage the rear of the patient's head, another portion in position to engage the back of the shoulders and another portion in position to positively engage the top of the head of the patient, and a jaw retractor pivoted to the support and at a point to the rear of that occupied by the condyles of the inferior maxillary of the patient, the jaw retractor having a portion for engaging the point of the chin of the patient.

3. A dental bite apparatus comprising a support having two positively engaging points for engagement with a patient's head, a jaw retractor pivoted to the support on a substantially horizontal axis to the rear of the position occupied by the condyles of the inferior maxillary of the patient, a shaft upon which the retractor is pivoted and means for pivoting the shaft for movement in a vertical plane.

4. A dental bite apparatus comprising a support having two positively engaging points for engagement with a patient's head, a jaw retractor pivoted to the support on a substantially horizontal axis to the rear of the position occupied by the condyles of the inferior maxillary of the patient, a shaft upon which the retractor is pivoted, means for pivoting the shaft for movement in a vertical plane and means for adjusting the pivoting means to draw the retractor against the chin of the patient.

5. A dental bite apparatus comprising a support, the support having a flat back member of a size and shape to engage the back of the shoulders and head of a patient, and also having a top board hinged to the flat back member and having limited movement therewith, a jaw retractor having a flexible chin-engaging member and two relatively stiff side members, a swivel plate attached to the rear of the back member, a screw having

a swivel connection to the swivel plate, a nut on the screw and adjustable therealong when the screw is turned, a shaft secured to the nut and having the retractor side members 5 pivoted thereon.

6. A dental bite apparatus comprising a support, the support having a flat back member of a size and shape to engage the back of the shoulders and head of a patient, and 10 also having a top board hinged to the flat back member and having limited movement therewith, a jaw retractor having a flexible chin-engaging member and two relatively stiff side members, a swivel plate attached 15 to the rear of the back member, a screw having a swivel connection to the swivel plate, a nut on the screw and adjustable therealong when the screw is turned, a shaft secured to the nut and having the retractor side members 20 pivoted thereon, the retractor side members being adjustable along the shaft.

7. A dental bite apparatus comprising a support, the support having a flat back member of a size and shape to engage the back

of the shoulders and head of a patient, and 25 also having a top board hinged to the flat back member and having limited movement therewith, a jaw retractor having a flexible chin-engaging member and two relatively stiff side members, a swivel plate attached to 30 the rear of the back member, a screw having a swivel connection to the swivel plate, a nut on the screw and adjustable therealong when the screw is turned, a shaft secured to the nut and having the retractor side members 35 pivoted thereon, the swivel, screw, nut, shaft and pivotal connection to the side members being such as to permit the shaft to pivot in a plane substantially parallel to the back member, to permit the side members to 40 be adjusted along the shaft and to permit the movement of the nut along the screw to tighten the retractor on the chin of the patient.

In testimony whereof I hereunto affix my 45 signature.

THOMAS J. BURGESS.
